(57) **CLAIM**

The ornamental design for a bottle, as shown and described.

DESCRIPTION

FIG. 1 is a top perspective view of a first embodiment of a bottle, which is useful for housing household and/or personal care compositions, particularly fabric care compositions;

FIG. 2 is a front view thereof;

FIG. 3 is first side view thereof;

FIG. 4 is rear view thereof; and

FIG. 5 is a second side view thereof, opposite the first side view of FIG. 3;

FIG. 6 is a top view thereof; and

FIG. 7 is a bottom view thereof;

FIG. 8 is a top perspective view of a second embodiment of a bottle;

FIG. 9 is a front view thereof;

FIG. 10 is first side view thereof;

FIG. 11 is rear view thereof; and

FIG. 12 is a second side view thereof, opposite the first side view of FIG. 10;

FIG. 13 is a top view thereof; and

FIG. 14 is a bottom view thereof;

FIG. 15 is a top perspective view of a third embodiment of a transparent bottle;

FIG. 16 is a front view thereof;

FIG. 17 is first side view thereof;

FIG. 18 is rear view thereof; and

FIG. 19 is a second side view thereof, opposite the first side view of FIG. 17;

FIG. 20 is a top view thereof; and

FIG. 21 is a bottom view thereof;

FIG. 22 is a top perspective view of a fourth embodiment of a transparent bottle;

FIG. 23 is a front view thereof;

FIG. 24 is first side view thereof;

FIG. 25 is rear view thereof; and

(Continued)

FIG. 26 is a second side view thereof, opposite the first side view of FIG. 24;

FIG. 27 is a top view thereof; and,
FIG. 28 is a bottom view thereof.

The broken lines in the figures illustrate the portions of the bottle that form no part of the claim. The drawings include surface shading that illustrates contour and not surface ornamentation.

1 Claim, 12 Drawing Sheets
